[57] ABSTRACT

An ironing press wherein the heating plate suspended to a pivoting arm is adapted to be lowered onto and raised above the ironing area, and wherein a hand-operable lock may be rocked into a position wherein a bolt carried by it engages a groove in the arm so as to lock the lever in the position it assumes inside the groove when it urges the arm downwardly. Furthermore, the lowering of the arm acts mechanically through the lever or through said lock on an electric circuit so as to disconnect the latter from the heating means which it energizes inside the heating plate and to connect it with an alarm circuit. A delay system is advantageously incorporated with said circuit to delay said switching operation a few seconds after the lowering of the arm and plate.

ELECTRIC IRONING PRESS

The present invention has for its object an electric ironing press comprising a working surface extending over a support to which an arm is pivotally secured around an axis which is substantially parallel with the working surface, a heating plate carrying heating means adapted to be connected with the electric mains, a system for suspending the heating plate to the arm and a hand-controlled lever pivotally secured to the arm at a point remote from said pivotal axis, said lever being provided with an extension cooperating with the support, so as to make the heating plate assume selectively two stable positions corresponding respectively to a closing and to an opening of the press.

The improved press according to the present invention is characterized by the provision of a mechanical safety and an electric safety system.

The accompanying drawings illustrate diagrammatically and by way of example an embodiment of the ironing press forming the object of the invention. In said drawings:

FIG. 1 is a perspective view of the improved ironing press.

FIG. 2 is an enlarged elevational view thereof, partly in section, with parts broken away, showing how the press is locked when in its closed position.

FIG. 3 is a top plan view of a part of the arm of the press, with parts broken away, to show how the press is locked when in its closed position.

FIG. 4 is a partial sectional view of a part of said arm, showing how the bolt-carrying-bar may act as a safety system when the press is in its open position.

FIG. 5 is a circuit diagram of the electric safety system.

FIG. 6 is a top plan view of a portion of the press, certain parts being broken away to show the electric safety system.

The electric ironing press illustrated in FIG. 1 comprises a frame or support 1 carrying an ironing board 2 covered by a fabric. An arm 3 from which a heating plate 4 is suspended, which acts as a sad-iron is pivotally secured to the rear end of the frame 1 around a horizontal axis. A hand-operable lever 5 which is pivotally secured to the arm 3 at a point remote from said horizontal axis cooperates with the profiles of two cams, which are not illustrated, carried by the frame and ensuring the opening and the closing of the press.

The arm 3 encloses a portion of the arrangement adapted to adjust the temperature of the heating plate 4. A thermostat-adjusting knob 6 fitted on the heating plate 4 is shown in FIG. 1, together with a luminous signal which is extinguished when the thermostat switches off the electric current feeding the heating means in the plate 4 and a panel 8 providing an indication for the desired temperature to be assumed by the heating plate 4.

As illustrated in FIGS. 1, 2 and 3, the arm 3 is provided with a groove 37 engaged by the lever 5 in its press-closing position.

A lock 38 controlled by a key which may be inserted in a bore formed for this purpose in the upper surface of the arm 3 is adapted to lock the lever 5 in its press-closing position. For this purpose, the bolt 39 on the lock 38 projects into the groove 37 engaged by the lever 5 in its press-locking position. This eliminates all

risks of an undesired inadvertent opening of the press when it is being put aside or taken hold of by unauthorized persons.

Similarly, when the press is open, the locking of the lock 38 prevents the press from being closed by an unauthorized person, since its bolt 39 prevents any lowering of the lever 5 into the groove 37, the bar 5 engaging the groove 37 for both positions of the lever. The lock 38 serves then as a safety system if, for instance, children were to try to close the press during a short absence of the actual operator. Preferably, the lock 38 controls a switch, not shown, which cuts off the electric circuit feeding the heating means of the press when lock 38 is in closed position and locking the press.

As illustrated, there is provided a second lever 40 rigid with the arm 3 of the press and through which the heating plate 4 may be shifted by hand towards the ironing board before the lever 5 is set in its press-closing position.

FIG. 5 shows the electric safety system controlling the current feeding the heating means and adapted to switch off the current when the press remains closed over a period which lasts too long, say over 15 seconds.

The circuit extends between two terminals *a* and *b* adapted to be connected with the terminals of one-phase mains. Heating means 9 are inserted in series with adjusting means 10 and a switch 11 between the terminals *a* and *b*. The adjusting means 10 include in particular the thermostat referred to hereinabove.

The switch 11 feeds the heating means when it is set in the position illustrated, whereas it releases an acoustic signal 12 when it is set in its other operative position.

The switch 11 comprises the contact pieces of a relay controlled by the energizing winding 12 subjected to the action of an electronic delaying system or timer. The latter is fed by the mains through a rectifier 14, a resistance R_1 and a Zener diode D_1 which stabilizes at a value of 24 volts the voltage of a condenser C_1 inserted in parallel with a condenser C_1 and loaded by the current from the mains after rectification at 14. Said delaying system includes a transistor T_1 adapted to load under constant current conditions a condenser C_2 . To this end, the base-emitter circuit of the transistor T_1 is stabilized by a further Zener diode D_2 and the resistances R_2 and R_3 .

The condenser is adapted to be discharged into a resistance R_4 upon closing of a switch S . The voltage of said condenser C_2 is applied to an amplifier of the Darlington type constituted by two transistors T_2 and T_3 and controlling the feed of the winding 13 forming part of the relay switch 11. A Zener diode D_3 is inserted in series between the condenser C_2 and the amplifier, so that the latter may become conductive only when the voltage of the condenser C_2 rises above the critical voltage of the Zener diode D_3 .

A resistance R_5 is provided for adjusting the voltage of the base of the transistor T_2 while a condenser C_3 inserted in series with a resistance R_6 cuts off all stray oscillations in the circuit. A diode D_4 is inserted in parallel with the winding 13, so as to quench the break impulses.

The switch S is opened by the lock 38, for instance, when the press is closed, so as to ensure the loading of the condenser C_2 . The voltage on the latter increases gradually and after about, say 15 seconds, it reaches

the threshold of conductibility of the diode D_3 , which results in the energization of the winding 13 of the relay switch 11. Consequently, the feed current is switched off and the acoustic signal 12 is released. If the press is now opened before the winding 13 is energized, this produces a closing of the switch S, whereby the condenser C_2 discharges speedily into the resistance R_4 . Thus, when the press is again operated, the condenser C_2 must be re-loaded, starting from a practically zero voltage.

The delaying system forms a printed circuit constituted by a thin plate 15 fitted in the arm 3 (FIG. 6). Said plate carries a conductive blade 16 playing the part of the switch S of FIG. 5 and providing for the contact between two contact-pieces, not illustrated, carried by the plate 15. Upon closing of the press, that is upon lowering of the arm 3, one end 17 of the conductive blade 16 is raised by a cam which is not illustrated, which cam is actuated by the lever 5, so that the contact between the contact-pieces through the blade 16 is cut off.

According to a modification, the acoustic signal 12 may be replaced by any other signalling means such as a luminous signal for instance.

We claim:

1. In an ironing press comprising a frame provided with a working area, an arm adapted to rock between an upper and a lower position with reference to said frame around an axis substantially parallel with the working area and provided with a groove extending across its upper surface perpendicular to said axis, a heating plate suspended from said arm, heating means within said heating plate and a hand-operable lever pivotally secured to said arm at a point remote from said axis and adapted to be shifted between an upper position raised above the arm for opening the press and a lower groove-engaging position for closing the press, the provision of mechanical lever-locking safety means in said arm and of an electric safety circuit also in said arm and opened and closed by actuation of said lever-locking safety means to make the heating means inop-

erative at a predetermined moment after the closing of the press.

2. A press as claimed in claim 1, wherein the mechanical safety means includes a lock including a bolt, the bolt of said lock penetrating inside the groove in the arm over the location, to thereby lock said lever in said last-mentioned position.

3. A press as claimed in claim 1, wherein the mechanical safety means includes a lock including a bolt 10 mounted in the arm, the bolt of said lock penetrating inside the groove in the arm over the location of the lever when said lever is in its lower groove-engaging position, thereby to lock said lever in said last-mentioned position, the movement of the bolt inside the groove 15 preventing the lever from entering said groove when the lever is raised above the arm.

4. A press as claimed in claim 1, wherein the mechanical safety means includes a lock including a bolt mounted in the arm, the bolt of said lock penetrating 20 inside the groove in the arm over the location of the lever when said lever is in its lower groove-engaging position, to thereby lock said lever in said last-mentioned position and wherein the electric circuit includes a switch controlled by the lock, said switch controlling 25 the operation of the heating means.

5. An ironing press as claimed in claim 1, wherein the electric safety circuit includes a timer controlling the electric current fed to the heating means, said timer being started when rocking the arm into its lower position 30 and being adapted to switch off the heating means at a predetermined time after the press has been closed.

6. An ironing press as claimed in claim 1, wherein the electric safety circuit includes a timer controlling the electric current fed to the heating means, said timer being started when rocking the arm into its lower position 35 and being adapted to energize a relay controlling a two-way switch at a predetermined time after the press has been closed, whereby the heating means are 40 switched off and an alarm signal energized.
